his Attorney.

UNITED STATES PATENT OFFICE.

THOMAS C. YOUNG, OF GLENDALE, CALIFORNIA.

ELECTROTHERMAL HYDRO-ETHER CONE.

1,268,529.

Specification of Letters Patent. Patented June 4, 1918.

Application filed June 7, 1917. Serial No. 173,262.

To all whom it may concern:

Be it known that I, THOMAS C. YOUNG, a citizen of the United States, residing at Glendale, in the county of Los Angeles and 5 State of California, have invented a new and useful Electrothermal Hydro-Ether Cone, of which the following is a specification.

This invention relates to means for applying ether as an anesthetic. The main object of the invention is to provide for supplying moisture along with the ether in such manner as to make the ether more effective, enable less ether to be used, produce anesthesia 15 more quickly and with less harmful effect on the patient.

Another object of the invention is to provide for effective regulation of the temperature at which the ether is supplied so as 20 to prevent chilling of the lungs or of the blood stream, and avoiding the danger of nephritis or other pathological condition, resulting from such cooling effects.

Another object of the invention is to provide for steady application of the ether, in such manner that the rate of supply does not depend on heat supplied by the breath of the patient, and more definite results can be secured when the breathing is irregular.

30 A further object of the invention is to provide for the prevention of post-operative shock.

Other objects of the invention will herein-after appear.

35 In the accompanying drawings,

Figure 1 is a side elevation, partly broken away, of a device embodying my invention.

Fig. 2 is a plan view thereof, with the cloth jacket removed.

40 Fig. 3 is an inverted plan view of the cone, with the pneumatic pad device and holder removed.

Fig. 4 is an inverted plan with the pad in place.

45 Fig. 5 is a section on line 5—5 in Fig. 1, showing one of the heating elements.

Fig. 6 is a section on line 6—6 in Fig. 2.

Fig. 7 is a transverse section of the holder for the pneumatic pad.

50 The invention comprises a cone 1 formed with a chamber 2 open at its lower end so as to extend over the nose and mouth of the patient, and provided with means for supply of ether and of water thereto, and with means for heating the same. Said cone may be of sheet metal, and may be formed

with inside and outside walls 3 and 4 and top and bottom walls 5 and 11, with a space 9 between said walls for receiving the heating means. At the upper end of the cone 1 a funnel 6 is provided, said funnel being preferably formed with a vertical partition 6', so as to provide a funnel portion 7 for receiving ether and a portion 8 for receiving water. The funnel portion 7 may open 65 directly into the upper end of the chamber 2, so as to allow ether supplied to such funnel to drop directly onto a cloth 10 supported within said chamber; but the water supply portion of the funnel preferably 70 communicates with pipes or fine tubes 13 which extend down within the chamber 2, close to the walls thereof, so as to more effectively distribute the water to said cloth.

Tubes or hollow studs 15 extend through 75 the double walls of the cone so as to admit air to the chamber 2, and I also prefer to provide a larger tube 16 through such wall at each side, closed normally by a sliding closure or gate 17 mounted to move in 80 guideways 18 with sufficient friction to hold the same in whatever position it may be placed.

The evaporating cloth 10 is preferably 90 mounted on a separable member or frame 20, carried by a collar member 21 which fits against the bottom of the cone 1 and is secured thereto by loops 22 on member 21 engaging over pins 23 on the cone, said collar member having an opening communicating with chamber 2. Frame 20 may consist of wires extending upwardly from member 21 and crossing one another so as to extend upward within the chamber 1 and to hold the cloth in approximately cone 95 shape, close to the conical wall of chamber 2. Member 21 may also serve to hold a pad or cushion 24, preferably pneumatic, and consisting for example, of a soft rubber tubular collar conforming to the shape of member 21 and having an inflating tube 26.

The heating means preferably consists of 100 heating elements 27 and 28 mounted within the space 9 aforesaid and consisting for example of resistance wires 28 wound on mica strips 30, said wires of the heating elements being connected to suitable means for supplying current thereto. For this purpose the two wires of a twisted cord supply circuit may be brought in through a hole 34 in 110 an insulator 35 mounted in a lateral extension 36 from the outer wall of cone 1, one

wire, indicated at 38 being connected to one of the heating elements aforesaid and the other wire 39 being connected to a thermostat 40 from which a wire 41 leads to another of the heating elements, said heating elements being connected in series by suitable wires, so that when the wires 38 and 39 are in connection through a suitable wall plug or otherwise with a supply circuit, and 10 the thermostat 40 is closed, current will flow through all of said heating elements. Thermostat 40 is preferably provided with a regulating screw 44 whereby it may be adjusted to cut off the heating current at any 15 desired temperature. A thermometer 45 may be provided at the upper part of chamber 2 for checking the temperature by actual observation. I prefer to provide a jacket or cloth covering 46 for the device secured 20 thereto in any suitable manner, and inclosing the same in such manner as to retain the heat in the device and prevent overheating the operator's hand. I prefer to make the outer wall 4 of cone 1 of aluminum, so as to 25 retain the heat in the cone, and to make the inner wall 3 of copper to conduct the heat more readily to the evaporating chamber within the cone.

The operation is as follows: The pneumatic pad 24 having been inflated, the cloth 10 placed over the frame 20 and holder 21 secured on the bottom of the cone 1, the device is placed over the nose and mouth of the patient, and current is supplied through 30 wires 38 and 39 so as to warm the cone. Ether is then supplied through funnel portion 7 and water through funnel portion 8, and the water running down through tubes 13 is distributed on to the cloth 10 so that 35 the ether which also falls on to such cloth and is evaporated therefrom is mixed with water vapor, the heat supplied by the electric heating means being sufficient to maintain a temperature most suitable for the 40 evaporation of the ether and water and to prevent chilling such as would otherwise result from the rapid evaporation. By maintaining the temperature in this manner I not only insure steady and regular 45 evaporation of the ether, but prevent chilling of the air passing to the patient's lungs, thereby avoiding injurious effects that are liable to result from such chilling, such as post-operative shock, nephritis, or other 50 pathological condition due to chilling of the blood stream.

In case the patient is lying on his side, the cone is applied in the same manner but in

that case one of the side faces of the cone will be presented upwardly and the gate in 60 such face will be opened so as to allow ether and water to be dropped through the opening 16 thus uncovered. Said gates may also be opened when the device is being used in ordinary position, so as to admit more air 65 for inhalation when necessary. The extension 36 of the casing is in communication with the interior chamber between the outer and inner walls of the cone 1, so that the thermostat is responsive to the temperature 70 adjacent to the walls of the chamber 2, and cuts off the heat when the temperature in chamber 2 rises to the point for which the thermostat has been set. Undue heating is thus avoided, while at the same time enough 75 heat is insured to thoroughly evaporate the ether and water and prevent accumulation of ether in drops, which would produce irregular evaporation and loss of anesthetic effect. 80

What I claim is:

1. Means for application of mixed vapors of water and ether, comprising an outer casing, an inner casing mounted therein by means of upper and lower transverse wall portions extending between said casings so as to form a closed space between said casings and said walls, electric heating means mounted in said space, a lateral projection on said outer casing having a compartment 90 therein communicating with said closed space, a thermostat mounted within said compartment and connected to control said electric heating means, a body of absorbent material and means for supporting such absorbent material within said inner casing, and means at the upper portion of said inner casing for supplying water and ether onto said absorbent material. 95

2. In means for application of mixed vapors of water and ether, a casing, a dome-shaped frame mounted on said casing and extending upwardly therein, an absorbent cloth supported on said frame, an ether supply funnel having an opening adapted to 100 deliver ether onto said absorbent cloth, a water supply funnel, and a plurality of tubes communicating with said water supply funnel and adapted to receive water therefrom and to distribute it to different 105 parts of said absorbent cloth. 110

In testimony whereof I have hereunto set my hand, at Glendale, California, this 28th day of May, 1917.

THOMAS C. YOUNG.
